UNITED STATES PATENT OFFICE

2,428,106

INTERNAL-COMBUSTION ENGINE

William Lawrence Wuehr, Port Arthur, Tex.

Application September 15, 1945, Serial No. 616,504

4 Claims. (Cl. 123—51)

1

This invention relates to an internal combustion engine of the opposed piston Diesel-type, and the primary object of the invention is to provide a smooth running engine of this kind capable of developing relatively great power.

More particularly, the present invention contemplates, in an engine of the above kind, the provision of a drive shaft having fly-wheel cam drums thereon, each cam drum receiving driving impulses at four spaced points from two pairs of opposed pistons in the operation of the engine.

A further object of the invention consists in providing the cam drums with peripheral cam grooves so designed that each cam drum receives two driving impulses from each pair of associated pistons for each revolution of the drive shaft.

A still further object of the invention is to provide, in an engine of the above kind, a novel arrangement of cylinders relative to a drive shaft having cam drums thereon, and novel driving mechanism between opposed pistons of the cylinders and the cam drums including walking beams, each operatively connected to corresponding pistons of two cylinders.

These and other objects and features of the invention will become apparent from the following description when considered in connection with the accompanying drawings, in which:

Figure 1 is a top plan view of an engine embodying the present invention.

Figure 2 is an enlarged vertical longitudinal section taken on line 2—2 of Figure 1 and partly broken away.

Figure 3 is a horizontal section taken on line 3—3 of Figure 2 and drawn on a reduced scale.

Figure 4 is an enlarged vertical transverse section taken on line 4—4 of Figure 3.

Figure 5 is a view partly in side elevation and partly in vertical section, with the engine partly broken away and drawn on a reduced scale.

Figure 6 is a fragmentary section drawn on the same scale as Figure 5 and taken on line 6—6 of Figure 3.

Figure 7 is a view similar to Figure 6, but with the pistons in different positions.

Referring in detail to the drawings, the engine is illustrated as including a suitable casing 5 within which are suitably mounted a plurality of sets of cylinders 6 which are parallel and open at their opposite ends. Each set of cylinders includes two pairs, and there are four sets of cylinders in the engine shown. Each cylinder has a central fuel injection valve 7 communicating with a fuel oil supply line 8 leading from a suit-

2

able source of supply of fuel oil under pressure. As is conventional in the art, each cylinder will have the usual air intake and exhaust ports.

A drive shaft 9, preferably of tubular form, so that a cooling medium may be circulated therethrough, has its axis extending transverse to the axes and centrally of the cylinders 6. The drive shaft is arranged between the pairs of cylinders so that one pair of each set is disposed above the shaft and the other pair of each set is disposed below the shaft. A fly-wheel cam drum 10 having a peripheral cam groove 11 is secured on the drive shaft between the cylinders of the pairs of each set. Opposed pistons 12 are provided in each cylinder and cooperate with each other in the innermost positions thereof to form a combustion chamber therebetween. Walking beams 13 are provided at opposite ends of each pair of cylinders, and the ends of each walking beam are connected to corresponding pistons of a pair of cylinders. Concentric rock shafts 14 and 15 are mounted at opposite sides of each cam drum between the cylinders of the pairs, the inner rock shaft 15 being journaled at 16 (Figure 4) in bearings carried by opposed walls of casing 5, and the outer rock shaft 14 being journaled on said inner rock shaft 15. One walking beam 13 is fixed on each one of the concentric shafts 14 and 15, and an arm 17 is fixed on each one of said concentric shafts and projects into the cam groove 11 of the associated cam drum 10. The connection of the ends of the walking beams with the pistons is effected by swinging connecting rods 18. It is noted that firing order of the upper pairs of cylinders is 1—5—3—7—2—6—4—8, while that of the lower cylinders is 2—6—4—8—1—5—3—7. It will be apparent that, by reason of the construction and arrangement shown and described, charges will be simultaneously ignited in an upper cylinder of each set at one side of the associated cam drum and in a lower cylinder of that set at the opposite side of said cam drum. There being opposed pistons in each cylinder, the associated fly-wheel cam drum on the drive shaft will simultaneously receive driving impulses at four spaced points from two pairs of opposed pistons. The arrangement insures a relatively smooth running engine capable of developing relatively great power, and this is enhanced by so designing the cam groove of each cam drum that two impulses are received by the cam drum from each pair of pistons for each revolution of the drive shaft. At the right side, the arms 17 and walking beams 13 are secured on the same

shaft, and such is true with respect to the lower left hand arms 17 and walking beams 13, as in Figure 4. The upper left hand arms 17 however, are secured on the outer shaft 14 and the adjacent upper walking beams 13 are secured on the inner shaft 15 and project through circumferentially extending arcuate slots provided at 19 in the associated outer shaft 14.

As the present invention is not specifically concerned with the fuel supply system and its parts, the same is not specifically shown or described herein and may be of any well known or preferred kind. The same also applies to the lubricating system, scavaging arrangement, etc. Anti-friction bearings for the shaft 9 may be provided at opposite sides of each cam drum 10 as indicated at 20, which bearings may be suitably sustained by the casing 5 or the cylinders 6, or both. As shown more clearly in Figure 5, it will be apparent that a walking beam is provided at each end of each pair of cylinders, the walking beams at corresponding ends of the upper and lower pairs of cylinders of each set being mounted on the same concentric rock shafts. As is also shown in Figures 6 and 7, when the pistons of a cylinder of one pair are in their innermost positions, the pistons in the cylinder of the other pair directly therebelow are in their outermost positions, and vice versa. By using a plurality of sets of cylinders, and setting the various cam drums in different positions, a substantially continuous drive for the drive shaft may be effected so as to secure an extremely smooth running engine almost free from vibration and generating relatively great power.

From the foregoing description, it is believed that the construction, operation and advantages of the present invention will be readily understood and appreciated by those skilled in the art. Minor changes may be made in the number, arrangement and form of parts illustrated and described, such as fall within the scope of the invention as claimed.

What I claim is:

1. In an internal combustion engine of the Diesel-type, at least two pairs of parallel cylinders open at their opposite ends, each of said cylinders having a central fuel injection valve, a drive shaft having its axis extending transverse to the axes of and located in a plane centrally between the ends of the cylinders and in a plane between the pairs of cylinders, a cam drum secured on the drive between the cylinders of the pairs and having a peripheral cam groove, opposed pistons in each cylinder cooperating with each other in the innermost positions thereof to form a combustion chamber therebetween, walking beams at opposite ends of each pair of cylinders, the ends of each walking beam being connected to corresponding pistons of a pair of cylinders, concentric rock shafts at opposite sides of the cam drum between the cylinders of the pairs, one walking beam being fixed on each one of said concentric shafts,

and an arm fixed on each one of said concentric shafts and projecting freely into the cam groove of the cam drum.

2. The construction defined in claim 1, wherein in the arms engage the groove of the cam drum at four substantially equally spaced points, and wherein the cam groove of the cam drum is designed so that two impulses are received by the cam drum from each pair of pistons for each revolution of the drive shaft.

3. The construction defined in claim 1, in combination with a casing enclosing the cylinders and walking beams, the inner ones of said concentric shafts being journaled in opposed walls 15 of the casing and having the outer shafts journaled thereon.

4. In an internal combustion engine of the Diesel-type, a plurality of sets of parallel cylinders open at their opposite ends, there being two pairs of cylinders in each set, each of said cylinders having a central fuel injection valve, a drive shaft having its axis extending transverse to the axes of and located in a plane centrally between the ends of the cylinders and in a plane between the pairs of cylinders, a cam drum secured on the drive shaft between the cylinders of the pairs of each set and having a peripheral cam groove, opposed pistons in each cylinder cooperating with each other in the innermost positions thereof to form a combustion chamber therebetween, walking beams at opposite ends of each pair of cylinders, the ends of each walking beam being connected to corresponding pistons of a pair of cylinders, concentric rock shafts at opposite sides of each cam drum between the cylinders of the pairs, one walking beam being fixed on each one of said concentric shafts, and an arm fixed on each one of said concentric shafts and projecting into the cam groove of the associated cam drum, the cam groove of each cam drum being designed so that each cam drum receives two impulses from each pair of associated pistons for each revolution of the drive shaft, the cam drums being relatively arranged so that firing of the charges in cylinders of the several sets is staggered and substantially continuous driving of the drive shaft is secured.
